UNITED STATES PATENT OFFICE.

ULYSSES S. ARMSTRONG, OF NEW KENSINGTON, PENNSYLVANIA, ASSIGNOR TO ARMSTRONG & WHITE, OF PITTSBURGH, PENNSYLVANIA, A CORPORATION OF PENNSYLVANIA.

FILING DEVICE.

Application filed December 22, 1926. Serial No. 156,447.

This invention relates to filing devices, more particularly to improvements in the construction and function of filing devices as commonly employed for filing letters, in voices, and the like.

It is among the objects of the invention to provide a filing device of simple, durable, mechanical construction embodying a minimum number of parts which shall be adapted to be manufactured by a few simple punching and bending operations whereby the cost of manufacture is reduced to a minimum.

The subject matter of the present invention relates to that type of filing devices which is used for temporary filing of paper sheets in large numbers such as bills, invoices or the like and accordingly the device is designed to permit the frequent addition and removal of papers from the file with facility and ease.

In the accompanying drawings constituting a part hereof and in which like reference characters designate like parts, Fig. 1 is a top plan view of a paper file embodying the principles of this invention; Fig. 2 is a longitudinal sectional view partly in elevation taken along the lines II-II, Fig. 1; Fig. 3 a vertical sectional view taken along the center line III-III of Fig. 1; Fig. 4 a development view of the metal base; Figs. 5 and 6 elevations of a movable lock and stop member located in the base in the manner and for the purpose as will be herein-after set forth; and Figs. 7 to 10, inclusive are views illustrating a cover member or name plate used to cover the central opening of the metal base.

Referring to the several figures of the drawings, the structure therein illustrated comprises a sheet metal base 1 adapted to be mounted and secured to a board or support 2 by screws 3 or in any other suitable manner.

As shown in the development view of Fig. 4, the base 1 comprises a single sheet metal punching provided with openings 4 and 5, a pair of elongated openings 6, a central opening 7, an upstruck portion 8 and cut-out portions 9 the latter having slots 10. The punching is formed or punched out to provide for folding the side portions 11 along the dotted line 12 and end portion 13 along the dotted line 14. One of the side

portions 11 also carries a slot 10, similar to 55 and aligned with slots 10 in members 9. The end portion 13 is provided with a lug 15 having an opening 16 therein to constitute an eyelet by which the filing device may be supported from a hook or nail. 60

The cut-out portions 9 formed in the central opening 7 are bent along the lines 17 in the same direction as are the side portions 11 and the end portion 13, thus forming a pair of lugs. The front portion is bent along lines 19 and 19' forming a depressed horizontal portion 19^a; and the sides of this portion are formed by bending its periphery along line 18 in the same direction as sides 11 and 13, as shown in Fig. 3. 70 The lug 15 is bent along line 15^a in the manner apparent from Fig. 3.

As shown in Figs. 2 and 3 a rod 20 having a pair of curved retaining arms terminating at 21 and having its axial portion offset as shown in Fig. 2 to form an arm having a notch 22 is disposed in the slotted opening 6 of the base by projecting the ends 21 therethrough, and pushing upwardly until shanks 20^a engage notches 9' of lugs 9. 80 As may be seen from Fig. 3, the arms 22^a of notch 22 are inclined forwardly when in a closed position. A binding strap 23, Fig. 6, having notches 23^a formed in it as shown and bent upwardly along lines 23^b and outwardly along lines 23^c to form a skirt and flange, is used to secure member 20 in its assembled position, as shown by Fig. 2. The notches 23^a engage shanks 20^a of retaining member 20 to hold the latter firmly in 90 notches 9'. After assembly, strap 23 is fastened to base 1 as by spot welding, soldering or riveting.

A spring rod 25 is disposed in the depressions 8 of the base as shown in Figs. 1 and 95 2 and in this position it engages the notch 22 of retaining member 20, to yieldingly restrain this member against movement.

In its closed position the arms of member 20 are at the front end of notches 6, and it 100 is movable only within the limits of these notches, as may be seen from Fig. 1. The effect of using the inclined notch in connection with the type of spring shown is as follows: In the opening or closing of member 20, the notch moves in a horizontally disposed flat arc and therefore adds but slight stress to the spring which functions 105

primarily to frictionally resist the movements of member 20.

The retaining member 20 is also adapted to be locked against movement in its normally closed position by means of a slide 26 having an up-struck portion 27. The slide is disposed in the slot 10, Fig. 4, and the up-struck portion 27 projects at one side of the base to provide for manipulation. The member 26 is provided with notches 28 which cooperate with the member 20 to rigidly lock it in place for one position of the slide and to permit its movement backward as shown by the dotted lines in Fig. 3 for another position of the slide.

A pair of vertically projecting filing posts 29 joined as a one piece member by the connecting portion 30, Figs. 3 and 1 are projected through openings 5 of the base and cooperate with the curved ends of the retaining member 20; as shown in Fig. 3. The upper ends of the posts 29 are in alignment with the curved ends of the member 20 to constitute an uninterrupted guide when closed for the perforations of the papers to be filed or secured therein.

The posts 29 may be secured to the base in any suitable manner as by welding the portion 30 to the base 1 as shown in Fig. 3.

Referring to Figs. 7 to 10 inclusive of the drawings, a cover plate 31 is provided for the opening 7 of the base and is preferably stamped or marked to constitute a name plate. The member 31 is provided with lugs 32 and a lug 33, the latter being provided with an up-struck or bead portion 34 as clearly shown in Figs. 8 and 9. The member 31 is adapted to fit over the opening 7 of the base by inserting the lugs 32 which are off-set as shown in Fig. 9 to fit underneath the top portion of the base 1. The member 31 is then pressed downwardly until the bead 34 is sprung underneath the opposite edge of the base members as shown in Fig. 9, whereby the cover is securely locked in position. The cover may be readily removed by springing the lug 33 a sufficient amount to raise the bead 34 above the edge of the base.

Referring to Figs. 1 and 3, which illustrate the complete assembly of the filing device with the retaining member in closed position, if it is desired to open the device for the purpose of removing papers from the filing posts 29 the slide member 26 is pressed inward against the base to bring the notches 28 in alignment with the retaining member 20 which however is held in its closed position by the tension of the spring member 25, with which it is engaged. The retaining member 20 may be laterally displaced in its open position as shown in Fig. 3 by moving it against the resistance of the spring 25 and when open the papers secured by their perforations in the filing posts 29

may be removed or added to as the case may be. The retaining member 20 is then forced back to its closed position in which it contacts with the posts 29 and the slide 26 is then pulled out of the base as shown in Fig. 1 to bring the shallow portions 28a of the notches 28 in register with the retaining member 20 to lock the same against movement. In its locked position the members 20 and 29 constitute uninterrupted guides for the papers which may be folded back or turned over by simply lifting them on the rods 29 and passing them over the arcuate portions of the member 20 and permitting them to drop down the vertical portion of the latter.

It is evident from the foregoing description of this invention that a filing device made in accordance therewith is of simple and inexpensive construction which can be readily manufactured in production quantities with a minimum cost of material and labor.

Although I have shown one of the embodiments of the invention it will be obvious to those skilled in the art that various modifications may be made in the details of construction and in the design and proportion of the several parts without departing from the principles herein set forth.

I claim:

1. A filing device comprising in combination a base having a plurality of filing posts consisting of an integral member projecting upwardly from the base and rigidly secured thereto, a plurality of integrally formed retaining arms in cooperative alignment with said posts and pivotally mounted on said base, and an elongate spring borne by the base, the axial portion of said retaining arms being provided with an offset section bearing upon said spring and movable in a flat arc lying in the general plane of the longitudinal extent of said spring, whereby said spring frictionally resists the opening and closing movements of said retaining arms.

2. A filing device comprising in combination a one-piece sheet metal base provided with a pair of downwardly extending lugs having notches therein, a retaining member disposed in said notches, a binding strap secured to said lugs for holding said retaining member therein, a pair of filing posts constituting an integrally formed member secured to the base in cooperative alignment with elongated openings provided in said base, said retaining arms being pivotally disposed in said openings and adapted to normally engage said filing posts, a spring borne by the base, the axial portion of said retaining arms being provided with an offset section bearing upon said spring and movable in a flat arc lying in the general plane of the longitudinal extent of said

spring, whereby said spring frictionally resists the opening and closing movements of said retaining arms.

3. A filing device comprising in combination a one-piece sheet metal base, a pair of filing posts projecting upwardly through openings in said base and constituting the receiving element for the material to be filed, a retaining element consisting of a pair of integrally formed curved upwardly

projecting rods pivotally mounted in said base and adapted to engage the tops of said filing posts, means for yieldingly restraining the retaining elements against pivotal movement in said base, and means for locking said retaining element in the position of its engagement with said filing posts. ¹⁵

In testimony whereof, I sign my name.

ULYSSES S. ARMSTRONG.
